UNITED STATES PATENT OFFICE

GEORGE E. JUBB AND ELMER B. LIBBY, OF ST. PETERSBURG, FLORIDA

SOLDERING TORCH

Application filed March 23, 1929. Serial No. 349,494.

This invention relates to new and useful improvements in electrode holders for spot welding, soldering or other devices for causing union.

5 The primary object of the present invention relates to a novel form of electrode holder permitting adjustment thereto whereby connections may be soldered in close fitting and out of the way positions.

10 With the above and other objects in view, the invention further consists of the following novel features and details of construction, to be hereinafter more fully described, illustrated in the accompanying drawing and 15 pointed out in the appended claims.

In the drawing:—

Figure 1 is a longitudinal sectional view taken through our improved type of torch.

20 Figures 2, 3 and 4 are horizontal sectional views taken on lines 2—2, 3—3 and 4—4 respectively through Figure 1 of the drawing.

25 Referring to the drawing in detail wherein like characters of reference denote corresponding parts, the reference character 10 indicates generally a tubular handle member having the end walls 11 and 12 therefor centrally apertured, as at 13 and 14 respectively. The interior of the housing is filled 30 with a suitable fireproof and heat resisting material which in this instance is of composite formation in the nature of one part plaster and two parts asbestos.

35 An attaching plug or tube, such as indicated at 15, and preferably formed of brass or other conducting material, is extended through the opening 14 in the end wall 12 of the handle member 10 and an appreciable distance within the packing carried thereby.

40 A conducting tube 16 is attached with the opposite end of the handle member 10 after the manner of the plug 15. The innermost projecting portion of the attaching tube 16 is provided with an attaching socket 17 into 45 which the adjacent end of the plug or tube 15 is received to establish a conducting connection therebetween.

50 Disk members 18 and 19 respectively, centrally apertured and slidably mounted upon the outer side walls of those portions of the

55 plug 15 and tube 16 within the handle member 10, dispose the outer surfaces thereof for contacting engagement with the adjacent inner sides of the end walls 11 and 12 of the handle. The outermost end of the conducting tube 16 is flattened and apertured to provide an attaching ear 20 for registration with a complementary ear 21, carried by an attaching socket 22, to facilitate accommodation of 60 a common fastening element 23 therethrough whereby a pivot mounting is established therebetween.

An electrode 24 having one end extended 65 within the bore of the attaching socket 22 is preferably formed of carbon and projected outwardly an appreciable distance therefrom. The outermost projecting end of the attaching plug or tube 15 has an annular depression or groove 25 within which the looped extremities 26 of a fastening grip 27 are sprung. Said grip is carried by a cable 28 having connection at its opposite end with a source of current 29. A conducting wire 30 joined at one end with the remaining pole or contact of the 70 source of current 29 carries a biting grip 31 at its opposite end. The source of current 29 may be either a low voltage battery, namely six volts, or the corresponding taps or binding posts of a step down transformer. 75

The interior of the conducting tube 16 may be filled with dry asbestos filler.

80 From the illustration of our invention in Figure 1 of the drawing, the method of the spot welding or solder is shown: the adjacent ends of wires are shown overlapped, the solder, whether rosin or acid core is interposed between the lap connection of the work and the adjacent end of the electrode 24. The low voltage current passing through the torch 85 will heat solder sufficiently to cause same to run and adhere to the overlapping ends of the wires but the heat will not be sufficient nor intense enough to cause the solder to run off or fry and spit as generally occurs with 90 overheated irons.

95 The biting clip 31, carried by the lead wire 30, is then grippingly engaged with one of the overlapping ends of the wires. The latter connection completes the circuit and contact- 100

ing engagement of the electrode 24 with the solder will instantly join the aforementioned overlapping free ends of the wires. It is to be noted that no current is used when the 5 electrode is disengaged from the solder or the clip 31 released from the work whereby the amount of voltage required for making the ordinary spot solder connection is equivalent to that of the flashing of the headlights of 10 a motor vehicle; the above comparison being drawn inasmuch as the improved torch may be effectively connected with the storage battery of a motor vehicle.

As a further safeguard against burning of 15 the hands when employing the improved torch in close places, we provide a protecting sleeve 32 telescopically associated with the conducting tube 16 as shown in Figures 1 and 3 of the drawing. The pivot connection 28 between the adjacent ends of the conducting tube 16 and the socket member 22 for the electrode 24 will permit of angular disposition of the latter to make or establish connections at 20 any place or from any angle.

25 The invention is susceptible of various changes in its form, proportions and minor details of construction, and the right is herein reserved to make such changes as properly fall within the scope of the appended claims.

30 Having thus described the invention, what is claimed is:—

1. A soldering torch comprising a tubular handle member having an insulation core, an 35 attaching plug extended axially within one end and core of the handle member, a conducting tube extended in like manner within the opposite end of the core and handle having an attaching socket receiving the adjacent end 40 of the attaching plug, an attaching ear formed upon the outermost projecting end of the conducting tube and an electrode holding socket having a complemental ear receiving a pivot pin therethrough common with the attaching ear, and the projecting extremity of 45 the attaching plug having an annular clip engaging depression.

2. A soldering torch comprising a tubular handle member having the end walls therefor 50 centrally apertured, an attaching plug extended through the aperture in one end wall of the handle, a conducting tube extended in like manner to the attaching plug through the 55 opposite end wall of the housing having a socket receiving the adjacent end of the plug, disk members carried upon those portions of the plug and tube within the handle and engageable with the adjacent surfaces of the 60 end walls therefor to space the plug and tube from the edges of the central apertures, an attaching ear formed upon the outermost projecting end of the conducting tube, and an electrode carrying socket having a complemental ear lying flush with and movable upon 65

the attaching ear to facilitate angular adjustment to the electrode therefor.

In testimony whereof we affix our signatures.

GEORGE E. JUBB. 70
ELMER B. LIBBY.
